(57) **CLAIM**

The ornamental design for a display with graphical user interface for a wearable sensor, as shown and described.

DESCRIPTION

FIG. 1 is a front view showing a display with graphical user interface for a wearable sensor;

FIG. 2 is a front view thereof, shown in an alternate position;

FIG. 3 is a front view thereof, shown in an alternate position;

and,

FIG. 4 is a front view thereof, shown in an alternate position. The stippling represents a contrast in appearance. The outermost broken line is for the purpose of illustrating the display and forms no part of the claimed design. The remaining broken lines illustrate portions of the graphical user interface that form no part of the claimed design.
